DOOR LATCH

Ronald W. Campbell, Jackson, Mich., assignor to Hancock Industries, Inc., Jackson, Mich., a corporation of Michigan

Filed June 2, 1958, Ser. No. 739,145

15 Claims. (Cl. 292—280)

This invention relates to latching mechanisms, and more particularly to latches adapted for use with automotive vehicle doors.

It is an object of the present invention to provide a novel and improved latching mechanism which is especially adapted for multi-toothed rotary bolts and which substantially minimizes the operational effort as well as the frictional wear which occurs during use of the latch.

It is also an object to provide an improved latching mechanism having the above characteristics, which may be of the free handle type in which the outside handle is freely movable when in locked condition, the invention providing means whereby repeated closing of the door over a long period will not affect proper adjustment of the parts which might result in malfunctioning of the mechanism.

It is another object of the invention to provide an improved latching mechanism of the rotary bolt type in which the detent means has relatively little inertia, and will therefore have a relatively rapid latching response when the door is slammed.

It is another object, in one form of the invention, to provide an improved latching mechanism of this nature which incorporates a keyless or self-locking principle.

It is a further object, in another embodiment of the invention, to provide an improved latching mechanism of the above character which is lockable from the outside by key operation.

Other objects, features, and advantages of the present invention will become apparent from the subsequent description, taken in conjunction with the accompanying drawings.

In the drawings:

Figure 1 is a perspective elevational view of one form of the invention which incorporates keyless locking, the mechanism being viewed from the inside in its unlocked condition;

Figure 2 is a perspective view similar to Figure 1 showing the parts in locked condition;

Figure 3 is a front elevational view of the mechanism shown in Figures 1 and 2 with the parts in unlocked condition, and illustrating the bolt and associated elements;

Figure 4 is a side elevational view of the mechanism shown in Figure 3, taken in the direction of the arrow 4 of Figure 3 and showing the outside rollback and coupling member;

Figure 5 is a side elevational view taken in the direction of the arrow 5 of Figure 3 and showing the inside rollback;

Figure 6 is a view similar to Figure 4 showing the parts in a momentary position described in detail below;

Figure 7 is a front elevational view, with parts broken away, of another embodiment of the invention which is generally similar to the embodiment of Figures 1-6 but is adapted for use with the rear door of a vehicle, the parts being shown in unlocked condition;

Figure 8 is a side elevational view taken in the direction

2

of the arrow 8 of Figure 7 and showing the outside rollback and coupling member;

Figure 9 is a side elevational view taken in the direction of the arrow 9 of Figure 7 and showing the inside rollback and locking lever;

Figure 10 is a front elevational view of another embodiment of the invention which is similar to that of Figures 1-6 but is adapted for outside locking by a key; and

10 Figure 11 is a side elevational view taken in the direction of the arrow 11 of Figure 10 and showing the outside rollback and associated parts.

In general terms, the invention comprises a latching mechanism having a mounting plate and a rotary multi-toothed bolt, the mounting plate being adapted to be secured at the outer edge of a door so that the bolt projects therefrom and is rotatable on a horizontal axis. Detent means are provided for holding the bolt in latching position, this detent means comprising two members independently movable on a common pivot. The first of these members has a first arm engageable with the rotatable bolt and a second arm engageable by an inside rollback for movement toward its unlatching position. A second member of the detent means has a first arm engageable by an outside rollback through a coupling member, and a second arm engageable with the second arm of said first member to urge the detent into unlatching position. The coupling member is shiftable between an unlocking position in abutting relation with said first 30 arm of the second detent member, and a locking position in which it is freely movable without engaging said member. Locking means are provided for shifting the coupling member and this means, in one embodiment of the invention, includes a novel resilient connection which 35 permits the door to be locked from the outside by slamming the door with the outside handle depressed and the coupling member in locking position. In an alternative embodiment, the locking means provides for key-operated locking from the outside. In the embodiments 40 of the invention intended for use on the front door of a vehicle, restoring means are also provided in the form of a kick-off portion on one of the locking means elements engageable by the first detent means member when the door is slammed or is opened from the inside.

45 Referring more particularly to the drawings, Figures 1-6 show an embodiment of the invention especially adapted for use on the front door of an automotive vehicle and which has means for keyless or self-locking from the outside. The latch is generally indicated at 21 and comprises a mounting plate generally indicated at 22 which is adapted to be secured at the outer or jamb edge of a vehicle door (not shown). Mounting plate 22 is of generally U-shaped construction, having a base portion 23, an outer flange portion 24, and an inner flange portion 25, flanges 24 and 25 being formed on opposite sides of the base. A multi-toothed rotary bolt generally indicated at 26 is mounted on base 23, this bolt having a plurality of bolt teeth 27 disposed outwardly of the base, as seen in Figure 4, and a corresponding number of latching or detent teeth 28 as seen in Figures 1 and 2. Bolt 26 has a shaft 29 supported on a horizontal axis between base 23 and an outboard bearing plate 31, seen best in Figures 3 and 4, this bearing plate being in spaced parallel relation with base 23 and secured thereto at its upper and lower ends. In the illustrated embodiment of the invention, a spring-urged takeup member 32 of wedged shape is slidably supported on a pin 33 carried by the upper portion of plate 31, this takeup member being spring-urged in a conventional manner against a keeper shown in dot-dash lines at 34 in Figure 4 which is secured to the stationary pillar and is adapted to enter between bolt teeth 27 and member 32 when the door is closed.

As best seen in Figures 1 and 2, detent means generally indicated at 35 are rotatably mounted on base 23 by a pin 36 disposed above bolt 26. The detent means comprises a detent member 37 having a first arm 38 engageable with ratchet teeth 28 and a second arm 39 which extends through a rectangular slot 40 in flange 25, as seen in Figures 3 and 5. Arms 38 and 39 extend in opposite directions, arm 38 extending downwardly and toward flange 24, with ratchet teeth 28 being so shaped that arm 38 will prevent counterclockwise rotation of the bolt as seen in Figure 3 when detent member 37 is in its latching position. A helical spring 41 has one end secured to base 23, the outer end of spring 41 engaging the underside of arm 39, so that detent member 37 will be urged in latching direction, a stop 42 of resilient material limiting the position of detent member 37 and minimizing noise when this member reaches its latching position. It will be noted, from an examination of Figures 1 and 2, that detent member 37 is closely adjacent to base 23, and the upper edge 43 of arm 38 is rounded in the manner shown in Figure 3 for purposes which will later appear.

The other element of detent means 35 comprises a transmitting and retaining lever 44 mounted on pin 36 outwardly of member 37. Lever 44 has a first arm 45 extending through a slot 46 in flange 24, as seen in Figures 3 and 4, and a second arm 47 extending in the opposite direction from arm 45, arm 47 having a transversely bent outer end which is disposed above an intermediate portion of arm 39 on detent member 37. It will thus be seen that when lever 44 is swung counterclockwise in Figure 3, it will cause detent arm 38 to be withdrawn from ratchet teeth 28, but that when detent member 37 is swung counterclockwise by the inside handle or by closing of the door, as will be later described, lever 44 will remain stationary. A raised retaining portion 48 is provided along the upper edge of lever arm 45, this portion serving to retain and guide another element of the assembly as will appear below.

Outer manually operable means in the form of a lever 49 is pivoted at 51 adjacent the lower end of flange 24, as seen in Figure 4. This lever, which may be termed an outside rollback, is adapted to be connected at one end 52 with a compression type of link indicated in dot-dash lines at 53 which is operable by an outside vehicle door handle (not shown). This type of handle is conventionally equipped with spring means urging link 53 upwardly. The opposite end 54 of rollback 49 has a pivotal connection 55 with the lower end of a coupling member 56 which extends upwardly therefrom. The coupling member has a shoulder 57 formed at an intermediate portion, and an elongated vertical slot 58 formed above the shoulder. Shoulder 57 is adapted to engage the underside of arm 45 immediately inwardly of flange 24 when the coupling member is in its unlocking position, as shown in Figures 1 and 4. When in this position, clockwise movement of rollback 49 in Figure 4 will force coupling member 56 upwardly, swinging detent means 35 to its unlatching position.

A locking lever 59 is pivotally supported by a pin 61 at the upper end of flange 24, this lever having an arm 62 connectible with a link shown in dot-dash lines at 63 which is operable by an outside key station (not shown). Lever 59 has a downwardly extending arm 64 with a bent end portion 65 disposed within slot 58, so that counterclockwise movement of lever 59 as shown in Figure 4 will move coupling member 56 to its locking position, as seen in Figure 2, in which shoulder 57 is withdrawn from arm 45. When in this position, unlatching rotation of rollback 49 will result in idling or ineffective movement of coupling member 56. Locking lever 59 has a third arm 66 extending toward base 23, and a lateral shoulder 67 is bent from lever 59 at the inner end of arm 66. A helical leaf spring 68 is secured at its inner end to lever 59 by retaining means 69 carried by a disc 71. The outer

end 72 of spring 68 rests on shoulder 67 and extends in spaced parallel relation with arm 66.

An inside rollback 73 is pivoted at 74 to an intermediate portion of flange 25, this rollback having a downwardly extending arm 76 connectible to a link shown partially in dot-dash lines at 77 which extends to an inside door handle (not shown). Rollback 73 has a second arm 78 extending toward base 23, this arm overlying arm 39 of detent member 37. Clockwise swinging of rollback 73 in Figure 5 by inside handle operation will thus cause detent arm 38 to be withdrawn from latching teeth 28. Rollback 76 is preferably held in a neutral position by conventional means (not shown) associated with the inside door handle. A lock operating lever 79 is pivoted at 81 to the upper portion of base 23, this lever having an arm 82 extending through a slot 83 in flange 25. Lever 79 is mounted closely adjacent to base 23 and in substantially the same plane as detent member 37. Inside rollback arm 78 is disposed beneath arm 82, so that counterclockwise movement of the rollback as seen in Figure 5 will result in clockwise swinging of lever 79 as seen in Figure 3. An overcenter spring 84 is connected between arm 82 and base 23 to hold lever 79 in either of its positions. It will be understood, of course, that instead of having an inside rollback 73 shiftable in opposite directions from an initial position, a separate button or lever could be connected directly to arm 82 to shift it between locking and unlocking positions, this button or lever being accessible from the inside of the door.

Lever 79 has a second arm 85 extending toward flange 24, the outer end of this arm being disposed between spring portion 72 and arm 66 of locking lever 59. Lever arm 85 also has a downwardly extending rounded restoring portion 86 which, when the lever is swung clockwise from its position shown in Figure 3 to the position shown in Figure 2, is closely adjacent edge portion 43 of detent member 37, so that unlatching movement of the detent member will restore lever 79 to its unlocking position as shown in Figures 1 and 3.

In operation of the embodiment shown in Figures 1-6, assuming an initial condition in which the parts are in their unlocked position as shown in Figures 1 and 4, and with the door closed, an operator desiring to enter the car will operate the outside handle, causing clockwise rotation of rollback 49 as seen in Figure 4. Coupling member 56 will move upwardly, and shoulder 57 of the coupling member will cause counterclockwise rotation of lever 44 as seen in Figure 3. This will cause detent member 37 to swing counterclockwise into its unlatching position so that the door may be opened. Upon release of the outside handle, the parts will be restored to their previous position. When the door is closed, clockwise rotation of bolt 26 as seen in Figure 3 will momentarily move detent member 37 to its unlatching position until arm 38 moves into latching relation with another tooth 28. During this movement, however, lever 44 will remain stationary, thus facilitating the latching operation since the moving parts will have relatively little inertia.

To lock the door from the inside, the operator will cause inside rollback 73 to be rocked counterclockwise from the neutral position shown in Figure 5. This will cause lever 79 to be rocked clockwise in Figure 3 to the position shown in Figure 2, overcenter spring 84 holding the lever in this position with rollback 73 returning to its neutral position. This movement of lever 79 will cause arm 85 thereof to engage arm 66, thus rocking lever 59 counterclockwise in Figure 4 to the position shown in Figure 2. This will cause withdrawal of coupling member 56 from opposed relation with arm 45 of lever 44. Subsequent operation of the outside door handle will thus merely result in idling movement of coupling member 56, the door remaining latched. At the same time, restoring portion 86 of lever 79 will be placed in closely adjacent relation with portion 43 of detent member 37.

Guide portion 48 of lever 44 will retain and guide restoring portion 86 of lever 79 during this movement.

Should the operator desire to leave the car, he will rock inside rollback 73 in a clockwise direction as seen in Figure 5, causing unlatching movement of detent member 37. At the same time, portion 43 of member 37 will engage portion 86 of lever 79, rocking this lever counterclockwise in Figure 3 to the position shown in Figure 2. Arm 85 will engage end 72 of spring 68, this spring being substantially stiffer than spring 84. This will cause locking lever 59 to swing to its unlocking position as shown in Figures 1 and 4, assuming that the outside handle is not depressed at this time. Coupling member 56 will thus be restored to its unlocking position, with shoulder 57 in opposed relation with arm 45 of lever 44.

After the operator has left the car, he may close the close door without depressing the outside handle, in which case detent member 37 will momentarily move to its unlatching position, the door remaining unlocked. If the operator thereafter desires to lock the door with the key, rotation of the key in the key station will cause upward movement of link 63, rocking lever 59 counterclockwise as seen in Figure 4 so that coupling member 56 will move to its locked position. Lever 79 will at the same time move to its locked position, as shown in Figure 2.

Should the operator desire to lock the door without use of the key, he will momentarily operate the inside handle to swing rollback 73 counterclockwise in Figure 5, thus shifting coupling member 56 to its locking position. He will then depress the outside handle, holding coupling member 56 in its raised position, and while doing so will slam the door. When this occurs, lever 79 will be momentarily swung to its unlocking position as shown in Figure 6 by movement of detent member 37. However, the engagement of arm 85 with spring end 72 will not cause lever 59 to swing clockwise in Figure 4, since edge 87 of coupling member 56 will engage the side of arm 45, preventing counterclockwise movement of coupling member 56 as seen in Figure 6. Therefore, arm 85 will deflect spring 68, and as detent arm 38 passes over the corresponding tooth 28, spring 68 will force lever 79 back to its locking position as seen in Figure 2, spring end 72 again engaging stop 67. The outside handle may now be released and coupling member 56 will return to its lower locked position as shown in Figure 2. To unlock the door from the outside, rod 63 will be operated from the key station to rotate lever 59 clockwise to the position shown in Figure 4.

It will be noted that in the operation of latch 21 described above, no movement of coupling member 56 or its associated lever 44 will occur when the door is opened from the inside or when it is slammed. This will not only lessen the frictional wear on these parts but will insure that they stay in proper relationship during continued use. This is especially important since the location of shoulder 57 with respect to arm 45 must be accurately maintained in order to prevent malfunctioning of the latch when moved between locked and unlocked conditions. The arrangement which permits keyless locking of the latch is therefore simple and foolproof in its operation and will greatly reduce maintenance costs.

Figures 7-9 illustrate another embodiment of the invention which is generally similar to that previously described but is especially adapted for use with rear vehicle doors in which both inside and outside handles are to be locked and which have no key locking provision. The latching mechanism is generally indicated at 101 and comprises a mounting plate generally indicated at 102 having a base 103 and flanges 104 and 105. Since the main portions of the latch are similar in structure and function to those of the previous embodiment, they will be briefly described. A bolt 106 is rotatably mounted on base 103 and cooperates with a detent member 107 pivotally mounted on the base, a transmitting lever 108 being mounted on a common pivot with member 107. An out-

side rollback 109 is pivoted on flange 104 and carries a coupling member 111 engageable with lever 108. A locking lever 112 is pivotally mounted on flange 104 and connected with coupling member 111, the locking lever having an arm 113 and a spring 114 in spaced parallel relation as in the previous embodiment. Lever 112, however, may omit the arm which would ordinarily be connected with the key station as illustrated in the previous embodiment.

5 10 An inside rollback 115 is pivoted at 116 on flange 105, this rollback having an arm 117 connectible with an inside handle (not shown) by a link shown partially in dot-dash lines at 118. Rollback 115 has a second arm 119 extending toward base 103 and overlying detent 107, as in the previous embodiment. In addition, a downwardly projecting locking extension 121 is provided on arm 119 for locking purposes as will be later described.

An inside locking lever 122 is pivoted at 123 on flange 105, this locking lever having a lateral shoulder 124 which

20 25 may be disposed in blocking relation beneath extension 121 of rollback 115 when locking lever 122 is shifted from its unlocking position as shown in Figure 9, in a clockwise direction to its locking position shown in dot-dash lines in this figure. Locking lever 122 is adapted to be moved between locking and unlocking positions by a button or lever (not shown) mounted on the inside of the door and connected to the locking lever by a link shown partially in dot-dash lines at 125. The upper portion of locking lever 122 has an inclined slot 126 within which is

30 35 disposed the outer end of an arm 127 formed on a lock operating lever 128 pivotally mounted on base 103. This lever corresponds with lever 79 of the previous embodiment and has an arm 129 disposed between arm 113 and spring 114 of lever 112. The position of slot 126 is such that when lever 122 is swung from its unlocking to its locking position, lever 128 will be cammed clockwise in Figure 7, thus swinging coupling member 111 to its locking position. An overcenter spring 131 is connected between base 103 and lever 128 as in the previous

40 45 embodiment. However, it will be noted that no restoring portion is formed on lever 128, arm 129 not being engageable by unlatching movement of detent member 107 even when lever 128 is in its locking position. Thus, the parts will remain in locked position even when the door is slammed.

In operation of the embodiment shown in Figures 7-9, the door may be opened from the outside or inside as in the previous embodiment. To lock the door, locking lever 122 will be swung to its dot-dash line position

50 55 in Figure 9, thus locking inside rollback 117 against unlatching movement and at the same time withdrawing coupling member 111 from its operative relation with lever 108. It will be noted that the advantages described with respect to the two-piece detent means in the previous

embodiment will also be present in the latch illustrated in Figures 7-9, since slamming of the door or opening from the inside will not be accompanied by movement of coupling member 111 or lever 108. It will also be noted that if the door is slammed after latch 101 is moved

60 65 to locked condition, the door will remain locked regardless of whether the outside door handle is depressed. Spring 114 and its associated parts will therefore not serve the same function as described with respect to latch 21, but are illustrated in order to indicate how standardized parts may be used for front and rear door latches incorporating the principles of the invention.

Figures 10 and 11 illustrate still another embodiment of the invention generally similar to the previous embodiments but which is especially adapted for the front door of a vehicle in which locking is to be accomplished from the outside only by key operation. The latch is generally indicated at 201 and comprises a mounting plate generally indicated at 202, this mounting plate having a base 203 and flanges 204 and 205. A bolt 206 is mounted on base 202 and has a detent member 207 for coopera-

tion therewith. A lever 208 is mounted on a common pivot with detent member 207 and extends towards flange 204, this lever cooperating with the detent member as in the previous modifications. An inside rollback 209 is pivoted on flange 205 and cooperates with detent member 207 as well as with a lock operating lever 211 pivoted on base 203, this lever being similar to lever 79 of the embodiment of Figures 1-6. An outside rollback 212 is pivoted on the lower portion of flange 204, and a locking lever 213 is pivoted to the upper portion of flange 204. The locking lever is adapted to be actuated by a link partially indicated in dot-dash lines at 214 which is connected with a key station (not shown) accessible from the outside of the door. The opposite end of lever 213 has a pair of rigid arms 215 in spaced parallel relation, these arms defining a slot 216 within which one end of lever 211 is disposed, as seen in Figure 11. A stop 217 is formed on flange 204 which limits the clockwise or unlocking position of lever 213.

A coupling member 218 is pivoted at 219 to the inner end of rollback 212, this coupling member extending upwardly from its connection with rollback 212 and having a finger 221 engageable by an arm 222 of lever 213 when this lever is swung counterclockwise from the position shown in Figure 11. Coupling member 218 is further provided with a shoulder 223 which is disposable beneath one end of lever 208 when the coupling member is in its unlocking position as shown in Figure 11. A positioning surface 224 is formed on coupling member 218, this surface taking the form of a shoulder extending transversely from the inner end of shoulder 223. The purpose of surface 224 is to limit the position of coupling member 218 in its unlocking position, this position being such that finger 221 will be spaced from arm 222. In this manner, vertical reciprocation of coupling member 218 during unlatching of the door from the outside will not be accompanied by frictional contact between finger 221 and the lateral end of arm 222. A spring 225 is mounted on pin 219 and engages rollback 212 and coupling member 218 so as to urge the coupling member counterclockwise in Figure 11 towards its unlocking position.

In operation of the embodiment shown in Figures 10 and 11, when it is desired to open the door from the outside, rollback 212 will be pivoted clockwise in Figure 11, causing shoulder 223 to swing lever 208 and detent member 207 counterclockwise in Figure 10, unlatching the door. During this movement, as indicated above, finger 221 will not rub against arm 222, thus maintaining these parts in friction-free relation. Opening of the door from the inside may be accomplished by rocking inside rollback 209 to move detent member 207 to its unlatching position, lever 208 and coupling member 218 remaining stationary. The latch may be moved to its locking position by opposite rotation of inside rollback 209, causing lever 211 to move clockwise in Figure 10, lever 213 moving counterclockwise in Figure 11 so that arm 222 engages finger 221 to withdraw shoulder 223 from opposed relation with lever 208. For this purpose, overcenter spring 226 which holds lever 211 in position will be substantially stiffer than spring 225. The restoring portion 227 of lever 211 will be disposed adjacent detent member 207 when lever 211 is in its locking position, as in the embodiment of Figures 1-6. With the parts in this position, movement of the outside handle will merely result in idling movement of rollback 212 and coupling member 218. To restore the parts to their unlocked position, link 214 may be operated to rock lever 213 to its clockwise position as shown in Figure 11, in which case spring 225 will cause shoulder 223 to enter into opposing relation with lever 208. Should the door be opened from the inside, lever 211 will be restored to its unlocking position, thus permitting coupling member 218 to move to its unlocking position under the influence of spring 225. Slamming of the door with the parts in locked position

will also result in restoring of coupling member 218 to unlocked position.

Locking from the outside may be accomplished by means of the key station, upward movement of link 214 causing counterclockwise movement of lever 213 from the position shown in Figure 11, and thus moving coupling member 218 to its locked position. Assuming that the parts are in locked position and the door is open, should the outside handle be inadvertently depressed while the door is slammed, the restoring means will cause levers 211 and 213 to move to their unlocking position, with arm 222 moving away from finger 221. Spring 225 will urge edge 228 of coupling member 218 against lever 221, and the parts will remain in this position until the outside handle is released, at which time coupling member 218 will move downwardly by virtue of spring means (not shown) previously mentioned which are associated with the outside handle. As soon as shoulder 223 clears lever 208, spring 225 will urge coupling member 218 counterclockwise into its unlocking position. It will thus be seen that the parts cannot be damaged by inadvertent depression of the outside handle when the door is slammed, even though this will have no effect as far as locking is concerned. The lock shown in Figures 10 and 11 could of course be adapted for rear door use by incorporation of a locking lever similar to that indicated at 122 in the embodiment of Figures 7-9 and elimination of the restoring feature.

While it will be apparent that the preferred embodiments of the invention disclosed are well calculated to fulfill the objects above stated, it will be appreciated that the invention is susceptible to modification, variation and change without departing from the proper scope or fair meaning of the subjoined claims.

What is claimed is:

1. In a latching mechanism, a mounting plate, a rotatable multi-toothed bolt on said mounting plate, detent means carried by said mounting plate and comprising a detent member and a transmitting lever on a common pivot, said detent member having an arm engageable with said bolt and movable between latching and unlatching positions, a second arm on said detent member, an inside rollback carried on said mounting plate and engageable with said second arm to move said detent member to unlatching position, overlapping portions on said detent member and transmitting lever whereby movement of said lever in one direction will cause unlatching movement of said detent member, an outside rollback carried by said mounting plate, means connecting said outside rollback and transmitting lever, and locking means for causing said connecting means to be separated from said transmitting lever, whereby said connecting means will be ineffective to move said lever when said outside rollback is operated.

2. In a latching mechanism, a mounting plate having a base and first and second flanges at opposite sides of said base, a rotary multi-toothed bolt on said base, detent means on said base comprising a detent member and a transmitting lever on a common pivot, said detent member having a first arm engageable with said bolt and movable between latching and unlatching positions, a second arm on said detent member extending towards said first flange, an inside rollback on said first flange engageable with said second arm of the detent member to move the detent member toward unlatching position, overlapping portions on said detent member and transmitting lever whereby movement of the transmitting lever in one direction will cause said detent member to move to unlatching position, an outside rollback mounted on said second flange, means connecting said outside rollback with said lever, and locking means movable to a position separating said connecting means from said lever and thus rendering said connecting means ineffective to transmit motion from said outside rollback to said lever.

3. The combination according to claim 2, said overlapping portions on the detent member and transmitting lever comprising an arm on said transmitting lever hav-

ing a portion overlapping said second detent member arm.

4. In a latching mechanism, a mounting plate having a base and first and second flanges on opposite sides of said base, a rotary multi-toothed bolt carried by said base, detent means carried by said base comprising a detent member and a transmitting lever independently mounted on a common pivot, a first arm on said detent member engageable with said bolt and movable between latching and unlatching positions, an inside rollback mounted on said first flange, a second arm on said detent member engageable by said inside rollback to move the detent member to unlatching position, overlapping portions on said detent member and transmitting lever whereby movement of the transmitting lever in one direction will cause unlatching movement of said detent member, an outside rollback mounted on said second flange, a coupling member extending between said outside rollback and said transmitting lever, and locking means for moving said coupling member between a transmitting position and a non-transmitting position with respect to said lever.

5. The combination according to claim 4, further provided with a lock operating lever pivotally mounted on said base and connected to said coupling member, said lock operating lever being movable between a locking position causing said coupling member to assume its non-transmitting position, and an unlocking position urging said coupling member towards its transmitting position, a restoring portion on said lock operating lever, and a portion on said detent member engageable with said restoring portion when the detent member is moved to its unlatching position to shift said intermediate locking lever to its unlocking position.

6. In a latching mechanism, a mounting plate, a rotary multi-toothed bolt on said mounting plate, detent means on said mounting plate movable between latching and unlatching positions with respect to said bolt, a rollback movably supported by said mounting plate, a coupling member between said rollback and said detent means, a locking lever pivotally supported by said mounting plate and movable between an unlocking position in which said coupling member is effective to couple said rollback and detent means, and a locking position in which said coupling member is ineffective to couple said rollback and detent means, a lock operating lever pivotally carried by said mounting plate, said lock operating lever being movable between locking and unlocking positions, a restoring portion on said lock operating lever in the path of said detent means when said lock operating lever is in its locking position, whereby unlatching movement of said detent means will move said lock operating lever to its unlocking position, an arm on said locking lever, and a spring on said locking lever in spaced relation with said arm, one end of said lock operating lever being disposed between said arm and spring of the locking lever whereby movement of said lock operating lever towards its unlocking position when said locking lever is in its locking position will be yieldably opposed by said spring.

7. The combination according to claim 6, said detent means comprising a detent member and a transmitting lever on a common pivot, said detent member having an arm engageable with said bolt, said transmitting lever being engageable by said coupling member when in its effective position, and overlapping portions on said transmitting lever and detent member, whereby movement of said transmitting lever in one direction will cause unlatching movement of said detent member.

8. In a latching mechanism, a mounting plate having a base and a flange, a multi-toothed rotary bolt on said base, detent means on said base engageable with said bolt and movable between latching and unlatching positions, said detent means having an arm extending towards said flange, a rollback mounted on said flange, a coupling

member pivoted on said rollback and extending towards said arm, a shoulder on said coupling member, the coupling member being swingable between an unlocked position in which said shoulder is in opposed relation with said arm and a locked position in which said shoulder is clear of said arm, the coupling member also being shiftable to unlatching position, a locking lever pivoted on said flange, a slotted connection between said locking lever and coupling member, the locking lever being swingable between locked and unlocked positions to move said coupling member between its locked and unlocked positions, a surface on said coupling member in opposed relation with said arm when said coupling member is swung to its locking position and shifted to its unlatching position, an arm and a spring in spaced relation on said locking lever, and a lock operating member carried by said mounting plate and having a portion disposed between said arm and spring, movement of said lock operating member in one direction causing engagement with said arm to swing said locking lever to its locking position, movement of said lock operating member in the other direction causing engagement with said spring to yieldably urge said locking lever towards its unlocked position.

25 9. The combination according to claim 8, said spring comprising a helical leaf spring having its inner end fastened to said locking lever, a flat portion at the outer end of said spring in spaced parallel relation with said arm, and a stop on said locking lever limiting the movement of said flat portion towards said arm.

10. The combination according to claim 8, said lock operating member comprising a lever pivoted on said base and movable between locking and unlocking positions, and an overcenter spring for holding said lock operating lever in either of said positions, said locking lever spring being substantially stiffer than said overcenter spring.

11. The combination according to claim 10, further provided with a restoring portion on said lock operating lever and in closely adjacent relation with said detent means when the lock operating lever is in its locking position, whereby unlatching movement of said detent means will restore said lock operating lever to its unlocking position.

12. The combination according to claim 8, said detent means comprising a detent member and a transmitting lever on a common pivot, said detent member having an arm engageable with said bolt, said transmitting lever being engageable by said coupling member and having a one-way connection with said detent member, said lock operating member comprising a lever pivoted on said base, said detent member and lock operating lever being mounted in the same plane and having substantially the same thickness, said transmitting lever being mounted alongside said detent member on the side thereof remote from said base, and a retaining portion on said transmitting lever extending toward and partially overlapping said lock operating lever, whereby said lock operating lever will be guided and retained by said retaining portion during its movement.

13. In a latching mechanism, a mounting plate having a base and a flange, a rotary multi-toothed bolt carried by said base, detent means on said base movable between latching and unlatching positions with respect to said bolt, said detent means comprising a detent member and a transmitting lever on a common pivot, said detent member having an arm engageable with said bolt, a second arm on said detent member, an inside rollback carried on said mounting plate and engageable with said second arm to move said detent member to unlatching position, an arm on said detent means extending towards said flange, an outside rollback pivoted on said flange, a coupling member pivoted to one end of said rollback and extending towards said last mentioned arm, a first shoulder on said

70 coupling member, the coupling member being swingable 75

between an unlocked position in which said shoulder is in opposed relation with said arm and a locked position in which said shoulder is clear of said arm, a spring urging said coupling member towards its unlocked position, a second shoulder on said coupling member engageable with said arm to determine the unlocked position of said coupling member, a finger on said coupling member, a locking lever pivoted on said flange and movable between locking and unlocking positions, a first arm on said locking lever engageable with said finger when said locking lever is moved to its locking position to swing said coupling member to its locked position, the position of said second shoulder being such that said finger is spaced from said first locking lever arm when the locking lever and coupling member are in their unlocked positions and when said coupling member is shifted in an unlatching direction, and means for shifting said locking lever between its positions.

14. The combination according to claim 13, said last-mentioned means comprising a lock operating lever pivoted on said base and movable between locking and unlocking positions, a second arm on said locking lever connected to one end of said lock operating lever, and a restoring portion on said lock operating lever disposable in closely adjacent relation with said detent member when the lock operating lever is moved to its unlocking position.

15. In a latching mechanism, a mounting plate having a base and first and second flanges on opposite sides of said base, a multi-toothed rotary bolt on said base, detent means on said base engageable with said bolt and movable between latching and unlatching positions, said detent means comprising a detent member and a transmitting lever on a common pivot, said detent member having a portion engageable with said bolt and movable be-

tween latching and unlatching positions, a first arm on said detent means extending toward said first flange, an outside rollback on said flange, coupling means between said outside rollback and detent means arm, locking means movably carried by said mounting plate and shiftable between an unlocking position in which said coupling means is effective to transmit movement between said outside rollback and detent means, and a locking position in which said coupling means is ineffective to transmit said movement, a second arm on said detent means extending towards said second flange, an inside rollback pivoted on said second flange and engageable with said second arm to move the detent means to an unlatching position, an inside locking lever pivoted on said second flange, a blocking portion on said inside locking lever, the inside locking lever being movable between a locking position in which said blocking portion is in obstructing relation with a portion of said inside rollback to prevent unlatching movement thereof, and an unlatching position in which said blocking portion is clear of said inside rollback, an inclined slot formed on said inside locking lever, and a lock operating lever pivoted on said base and having a first arm disposed within said slot and a second arm connected with said locking means, the shape of said inside locking lever slot being such that movement of the inside locking lever towards its locking position will cause shifting of said lock operating lever to move said locking means to its locking position.
